(57) **CLAIM**

The ornamental design for an input device for electronic and computer equipment as shown and described.

DESCRIPTION

The patent or application file contains at least one drawing executed in color. Copies of this patent or patent application publication with color drawing(s) will be provided by the Office upon request and payment of the necessary fee.

1. Input device for electronic and computer equipment Fig. 1.1 is a perspective view; Fig. 1.2 is a front view; Fig. 1.3 is a right side view; Fig. 1.4 is a left side view; Fig. 1.5 is a bottom view; Fig. 1.6 is a rear view; Fig. 1.7 is a top view; Fig. 1.8 is a front left side view; Fig. 1.9 is a rear right side view; Fig. 1.10 is a rear left side view.
